ALKYL PHENYLPIPERAZINYL- ALKYLCARBAMATES

John J. Lafferty, Levittown, and Charles L. Zirkle, Berwyn, Pa., assignors to Smith Kline & French Laboratories, Philadelphia, Pa., a corporation of Pennsylvania
No Drawing. Filed Oct. 4, 1966, Ser. No. 584,098
5 Claims. (Cl. 260—268)

ABSTRACT OF THE DISCLOSURE

Alkyl phenylpiperazinylalkylcarbamates have tranquilizing activity and are prepared by the reaction of a phenylpiperazinylalkylamine with a lower alkyl haloformate.

This invention relates to novel alkyl phenylpiperazinylalkylcarbamates having useful pharmacodynamic activity. More specifically the compounds of this invention have tranquilizing activity as measured by standard pharmacological procedures in animals. Exemplary of the activity shown by the compounds of this invention after oral administration is the increase in stimulus-producing response rate of pigeons, the block of avoidance behavior in monkeys and the decrease in fixed interval response rates of monkeys. These compounds are approximately equipotent to chlorpromazine.

The novel alkyl phenylpiperazinylalkylcarbamates of this invention may be represented by the following general structural formula:

FORMULA I

in which A represents an alkylene chain, straight or branched, of from 2 to 6 carbon atoms, preferably 2 to 4 carbon atoms, and R represents lower alkyl of from 1 to 4 carbon atoms.

A preferred compound of this invention is ethyl N-[3-(4-phenyl-1-piperazinyl)-propyl]-carbamate.

The nontoxic pharmaceutically acceptable acid addition salts of the compounds of Formula I are also included within the scope of this invention. Both organic and inorganic acids can be employed to form such salts, illustrative acids being sulfuric, nitric, phosphoric, hydrochloric, citric, acetic, lactic, tartaric, pamoic, ethane-disulfonic, sulfamic, succinic, cyclohexylsulfamic, fumaric, maleic, benzoic and the like. These salts are readily prepared by methods known to the art.

The novel compounds of this invention as represented by Formula I above are prepared by the reaction of the appropriate phenylpiperazinylalkylamine with a lower alkyl haloformate, preferably a chloroformate. The reaction is advantageously carried out in a nonreactive organic solvent such as chloroform or the like, preferably at room or ambient temperature, for periods up to 24 hours. The phenylpiperazinylalkylamine starting materials are known as described in the U.S. Patent No. 2,722,529.

The point of novelty of the herein described invention is the alkyl carbamate moiety and the unobviousness of the utility of such phenylpiperazinylalkylamine derivatives as tranquilizers. Phenyl ring substituted piperazinylalkyl carbamates are generically disclosed in U.S. Patent No. 2,836,595 useful in the treatment of hypertension and in the prevention of nausea and vomiting.

The novel compounds of this invention may be administered orally or parenterally in conventional dosage forms such as tablets, capsules, injectables or the like, by incorporating the appropriate dose of a compound of

2

Formula I with carriers according to accepted pharmaceutical practices.

The foregoing is a general description of how to prepare the compounds of this invention. The following examples illustrate the preparation of specific compounds but should not be construed as a limitation of the scope of the invention set forth in Formula I.

EXAMPLE 1

10 To a solution of 19.8 g. (0.09 mole) of 1-phenyl-4-(3-aminopropyl)-piperazine in 100 ml. of chloroform at 27° C. is added 4.9 g. (0.045 mole) of ethyl chloroformate in 50 ml. of chloroform. The mixture is stirred for one hour and allowed to stand at 27° C. for 17 hours. 15 The solvents are removed in vacuo and the crude residue is recrystallized from methanol-water to yield ethyl N-[3-(4-phenyl-1-piperazinyl)-propyl]-carbamate as the mono-hydrate, M.P. 53-54° C.

EXAMPLE 2

Employing the general procedures of Example 1, the following alkyl haloformates and phenylpiperazinylalkylamines are reacted to give the corresponding products:

(A)

20 Haloformate: ethyl chloroformate
Amine: 1-phenyl-4-(2-aminoethyl)-piperazine
Product: ethyl N-[2-(4-phenyl-1-piperazinyl)-ethyl]-carbamate

(B)

Haloformate: methyl chloroformate
Amine: 1-phenyl-4-(4-aminobutyl)-piperazine
Product: methyl N-[4-(4-phenyl-1-piperazinyl)-butyl]-carbamate

(C)

35 Haloformate: propyl chloroformate
Amine: 1-phenyl-4-(5-aminopentyl)-piperazine
Product: propyl N-[5-(4-phenyl-1-piperazinyl)-pentyl]-carbamate

(D)

40 Haloformate: ethyl chloroformate
Amine: 1-phenyl-4-(2-aminopropyl)-piperazine
Product: ethyl N-[2-(4-phenyl-1-piperazinyl)-propyl]-carbamate

45 What is claimed is:

1. A chemical compound selected from the group consisting of a free base and salts thereof with pharmaceutically acceptable acids, said free base having the formula:

55 in which A is an alkylene group of from 2 to 6 carbon atoms and R is lower alkyl of from 1 to 4 carbon atoms.

2. A chemical compound according to claim 1 in which A is n-propylene.

3. A chemical compound according to claim 2 in which R is ethyl, being the compound ethyl N-[3-(4-phenyl-1-piperazinyl)-propyl]-carbamate.

4. A chemical compound according to claim 1 in which A is ethylene

5. A chemical compound according to claim 4 in which R is ethyl, being the compound ethyl N-[2-(4-phenyl-1-piperazinyl)-ethyl]-carbamate.
